UNITED STATES PATENT OFFICE.

WILLIAM O. HARRIS AND FRANK C. KOHLER, OF SAN FRANCISCO, CALIFORNIA.

SAFETY PIN.

Application filed November 23, 1927. Serial No. 235,243.

Our invention relates to improvements in safety pins, and it consists of the combinations, constructions and arrangements hereinafter described and claimed.

- 5 An object of our invention is to provide a safety pin that has novel means for positively preventing the accidental opening of the pin. This means is so constructed that the point of the pin becomes wedged more tightly in closed 10 position in direct proportion to the increase of strain placed upon the point, and the pin will first break before the point can become accidentally disengaged when force alone is applied to the point.
- 15 A further object of our invention is to provide a device of the type described, that is, constructed from a single piece of wire, this wire not only being bent for preventing the accidental unfastening of the safety pin, but 20 also forming a guard that prevents the cloth from moving into the top of the pin, this guard also acting as a guide for causing the point to swing into proper position.

Other objects and advantages will appear 25 in the following specification, and the novel features of the device will be particularly pointed out in the appended claim.

Our invention is illustrated in the accompanying drawing forming a part of this application, in which Figure 1 is a side elevation 30 of the device;

Figure 2 is a section along the line 2—2 of Figure 1; and

Figure 3 is a section along the line 3—3 of Figure 1.

In carrying out our invention, we provide a safety pin constructed from a single piece of wire in the following manner: The wire is provided with a point 1, and an arm portion 40 2 that extends from the point to the spring portion 3. The wire is of resilient quality and will function in the same manner as the wire in a standard safety pin. The tendency of the arm 2 when released is to swing into the dotted line position shown in Figure 1. The wire is then fashioned into a back 4 for the pin and a head portion 5. From the head portion 5 to the point X the wire is bent into a curve as at 6. At the point X the wire is 45 bent back upon itself forming a like curve 6, a head portion 5, and then the wire is extended from the back 4 toward the curve 6 to provide a guard 7. At a spaced distance from the curve 6, the wire is bent back upon itself as at 8, and then the end is wrapped around 50 the back 4 as at 9.

The curved portions 6 are spaced from each other as shown in Figure 3, and form a wedge-shaped recess 10 for receiving the wedge-shaped end 11 of the point 1. The strain 60 upon the safety pin is on the arm 2, and is in the direction of the arrow shown in Figure 1. The tendency of the arm to bow in this direction will cause the arm to fulcrum about the point X and tend to force the wedge-shaped 65 member more tightly into the wedge-shaped recess. The wedge-shaped point 11 is larger than the recess 10, and therefore it cannot be forced through this recess. In fact, the greater the force applied on the arm 2, the 70 greater the wedging action, and the arm 2 will have to be really broken before the point 1 can be disengaged from the curved portions 6.

We also provide the guard 7, which takes 75 the place of the standard guard, and Figure 2 shows how this guard is spaced opposite one of the curved portions 6. The point 1 when swung into the recess 12 formed by the curved portions 6, is guided by the guard, 80 and the guard is spaced sufficiently far enough away from one of the curved portions 6 to permit the point to enter the recess 12 regardless of the fact of whether the point is moved into the recess from one side or the 85 other. In this way the guard acts as a guide, as well as prevents the cloth from moving up into the head 5. The cross-sectional shape of the wire forming the pin is not altered in any respect, with the exception of the point 1, and 90 in this respect the wire is flattened for providing the wedge shaped member 11. The device is extremely simple in construction, and is thoroughly efficient for the purpose intended. 95

Although we have shown and described one embodiment of our invention, it is to be understood that the same is susceptible of various changes, and we reserve the right to employ such changes as may come within the 100 scope of the appended claim.

We claim:

A safety pin comprising a single piece of wire having a wedge-shaped point formed by flattening one end of the wire at right angles 105 to the plane of the pin into a relatively thin structure and a wedge-shaped recess formed by the wire for receiving the point.
